DESIGN FOR A PAPER HOLDER

William Marcus, Cleveland, Ohio

Application November 15, 1946, Serial No. 134,797

Term of patent 7 years

(CL. D74—1)

To all whom it may concern:

Be it known that I, William Marcus, a citizen of the United States and resident of Cleveland, Cuyahoga County, Ohio, have invented a new, original, and ornamental Design for a Paper Holder, of which the following is a specification, reference being had to the accompanying drawing, forming a part thereof.

In the drawing, Fig. 1 is a side elevational view of a paper holder showing my new design, the opposite side presenting substantially the same appearance as the side shown; Fig. 2 is a top plan view; Fig. 3 is an end elevational view; while Fig. 4 is a fragmental sectional view taken along the line 4—4 of Fig. 2.

I claim:

The ornamental design for a paper holder, as shown and described.

WILLIAM MARCUS.
